[57] **CLAIM**

The ornamental design for a wall mounted fluorescent
lighting fixture, as shown and described.

DESCRIPTION

FIG. 1 is a perspective view of the wall mounted fluorescent
lighting fixture embodying the subject design;
FIG. 2 is an end elevation of the wall mounted fluorescent
lighting fixture of FIG. 1; the other end being a
mirror image thereof;

FIG. 3 is a rear elevation of the wall mounted fluorescent
lighting fixture of FIG. 1; and,

FIG. 4 is a bottom plan view of the wall mounted fluorescent
lighting fixture of FIG. 1.

FIG. 1

FIG. 2
